(57) **CLAIM**

The ornamental design for a wide lower fence rail retainer, as shown and described.

DESCRIPTION

FIG. 1 is a top view of a wide lower fence rail retainer showing my new design;

FIG. 2 is a left side view thereof;

FIG. 3 is a front view thereof;

FIG. 4 is a right side view thereof; and,

FIG. 5 is a bottom view thereof;

FIG. 6 is a back view thereof; and,

FIG. 7 is an isometric view thereof.

FIG. 8 is an environmental view thereof restraining a chain link fence to the ground. The chain link fence and ground shown in dashed lines are for illustrative purposes only and do not form part of the claimed design.
